UNITED STATES PATENT OFFICE.

GEORGE W. HILL, OF NEW YORK, N. Y., ASSIGNOR TO AMERICAN TOBACCO COMPANY,
OF NEW YORK, N. Y., A CORPORATION OF NEW YORK.

CIGARETTE-CASE.

1,119,281.

Specification of Letters Patent.

Patented Dec. 1, 1914.

Application filed March 26, 1913. Serial No. 756,902.

To all whom it may concern:

Be it known that I, GEORGE W. HILL, a citizen of the United States, residing at New York, in the county of New York and

5 State of New York, have invented new and useful Improvements in Cigarette-Cases, of which the following is a specification.

10 My present invention relates to certain new and useful improvements in pocket cigarette cases especially designed for use in connection with cigarettes that are packed in what are known as slide boxes.

15 The object of the invention is a provide, as an entirely new article of manufacture, a novel, attractive, and substantially constructed pocket case adapted to receive and retain the filled or packed cigarette-containing members of ordinary paper slide-boxes in such manner that one end of the paper 20 slide may be pushed from the case to enable the smoker to remove a cigarette or cigarettes when desired, and which may then be pushed back into the case for protection and convenience in carrying. The said case

25 thus serves as a permanent container in which the smoker may insert the packed or filled boxes or box-slides, either or both, as fresh boxes of cigarettes are purchased, a filled slide or box and slide being substituted 30 for an empty one when replenishing becomes necessary, thus avoiding the time, trouble and annoyance that is required in filling the known types of cases, wherein the cigarettes are placed therein by hand one 35 at a time.

In all the cigarette cases with which I am familiar, it is necessary when filling them, to place the cigarettes therein one at a time, taking the cigarettes from the original box or package and carefully arranging them in the case in regular order to prevent breaking or buckling. This filling or replenishing operation not only requires considerable time, trouble and annoyance, 45 but often results in some of the cigarettes so transferred becoming damaged to such an extent as to render them useless for smoking purposes, and the result is that these old style hand-filled cigarette cases 50 have never gone into general use, their use being the exception rather than the rule.

The cigarette case forming the subject matter of the present application is filled without any handling of the individual cigarettes and the case may be completely filled

or emptied in less time and with less trouble than it takes to transfer a single cigarette from its original box or package to one of the old style cases.

My improved cigarette case is simple and durable in construction, neat in appearance, and comparatively cheap to manufacture, and constitutes an entirely new and useful article of manufacture having peculiarly prominent physical characteristics that especially adapt it to the purposes and objects for which it is intended and clearly distinguish it from other forms of cigarette cases or containers.

In order to enable others to understand, 70 make and use my said invention, two preferred forms of which are herein disclosed, I will now proceed to describe the same in detail, reference being made for this purpose to the accompanying drawings, 75 wherein—

Figure 1 is a perspective view of one form or style of case made according to the invention. Fig. 2 is a similar view showing the case as containing a filled box slide, one 80 end of the slide being pushed out of the case to enable the withdrawal of one or more cigarettes. Fig. 3 is a longitudinal section on an enlarged scale, taken on the line 3—3 of Fig. 1. Fig. 4 is an end view of the 85 case shown collapsed. Fig. 5 is a perspective view of another style of case made according to the invention, a complete cigarette box being shown therein. Fig. 6 is a horizontal section taken on the line 6—6 90 of Fig. 5, the showing being somewhat exaggerated to more clearly illustrate the construction.

Referring to the drawings, and more particularly to Figs. 1, 2 and 3 thereof, which illustrate a cigarette case designed to receive a slide box as a whole, including both shell and slide, or simply the slide member of such a box containing a single row of cigarettes, the reference letter A designates the case proper which consists in the instance shown of a rectangular or box form shell having relatively broad upper and lower walls *a* and *b*, and opposite side walls *c*, the said shell being open at its opposite ends as shown to receive the original cigarette package comprising an inner slide box or cigarette container 4, such as shown in Fig. 2, which has the usual hinged closure flap 5. The shell of the case is prefer- 100 105 110

ably formed from a single strip of paper-board or other suitable material 6, bent or folded around a former, or otherwise suitably formed, the shape of the shell corresponding in general outline to the outline of the cigarette box or its slide-member that is slidably inserted therein and its interior dimensions being only so much larger than the cigarette box or its slide-member as to enable the ready insertion and withdrawal of either or both of such members, as the case may be, depending upon whether the case is constructed to receive both the box-shell and its slide-member or only the latter.

5 While the shell of the case should be made of a size to enable the ready insertion and removal of the cigarette box or its slide, there should however, be a sufficiently close fit between the parts to insure maintenance thereof in assembled condition, and prevent accidental displacement when carried in the pocket and when taken out for use. Inasmuch as these cigarette boxes and their slides are usually made of smooth-surfaced 10 or somewhat glazed paper, there is a tendency for the box or its contained slide to slip out of the case, and as will hereinafter appear I have provided a special construction to overcome this difficulty. In order to 15 make the shell 6, sufficiently durable to withstand the wear and tear to which it is naturally subjected during continued use, or in other words, to give it lasting qualities, and also to make it attractive, I cover the 20 entire external surface thereof with some suitable wear-resisting material 7, and for this purpose I prefer to employ a good quality of grained or pebbled leather, the marginal edges 8 of which are neatly turned 25 over and into the opposite open ends of the shell 6, and then pasted or glued to the inner walls of the shell as more clearly shown in Fig. 3. This manner of attaching the covering material exposes the grained or pebbled surfaces of the turned-in marginal portions or edges 8, for frictional contact with the outer walls of the cigarette box or its slide-member, as the case may be, at the opposite ends thereof, and constitutes a frictional retaining means to prevent accidental 30 displacement of the box or its slide relative to the case, but at the same time permits the box or its slide to be readily pushed out of or into the case when a cigarette is desired, or when a fresh supply of cigarettes 35 is being inserted into the case. The leather or other covering of wear-resisting material 7, is preferably formed from a single strip wrapped or wound about the outer surface 40 of the shell 6, and by preference only the marginal inturned portions 8, are pasted or glued to the shell, the portions overlying or covering the outer walls of the shell remaining free or unattached. This gives to 45 the case a somewhat padded appearance,

which adds to its general attractiveness and makes it soft and flexible, enabling it to be collapsed or flattened out as illustrated in Fig. 4, for convenience in packing and carrying when unfilled; the covering about the 50 bent or scored corners of the shell being of leather or a similar material is adapted to stand considerable tensile strain and enables the case to yield under pressure from within and adapt itself without injury to 55 slight variations which occur in the dimensions of the inner containers. By turning in the ends of the covering at the mouths or open ends of the shell the portion turned in and lying just within the mouth of the shell 60 operates to yieldingly choke or restrict the cross section of the mouth and at the same time reinforce the corners at this point inside, which reinforcing effect is added to the reinforcing effect of the flexible cover on the 65 outer side of the shell.

The form of case illustrated in Figs. 1 and 2, is shown as containing only the slide-member of a cigarette box carrying but a single row of cigarettes and for this reason 70 the case is relatively broad and shallow or thin. In Figs. 5 and 6, I have shown the case as constructed to receive a cigarette-box containing a double row of cigarettes, and the case is therefore narrower and 75 deeper than the form first above referred to. Inasmuch as I contemplate making my improved cases of dimensions suitable to receive either the original cigarette box-slide 80 or both the slide and its ordinary paper shell or casing, I have shown the case B, in Figs. 5 and 6, as containing both the box shell 9 and its slide member 10, the said case 85 being otherwise constructed identically like the case illustrated in Figs. 1 and 2, 90 although I may, if desired, and in some instances I prefer to slightly incline the side walls 12 of the case toward each other, as more clearly shown in Fig. 6, or in other words, make the case slightly narrower at 95 one end than at the other, so that when the box shell 9 is pushed into the case it will bind tightly therein at the narrower end so that it will not be accidentally pushed out along with, or will not follow the slide when 100 one end of the latter is being projected in the usual way for the purpose of withdrawing a cigarette, and this contracting of one end of the case will also prevent accidental displacement of both the box shell and its 105 slide-member when the complete cigarette box is inserted in the case, since the walls of all the parts are more or less flexible or yielding and pressure exerted by the contracted side walls of the case will be communicated to the box-shell and from the shell 110 to the side walls of the slide-member.

It will be seen from the foregoing that I have provided an entirely new and useful article of manufacture, involving a dis-

tinctly new inventive idea of means for carrying out the objects and purposes of the invention, and while I am aware that my improved cigarette case, so far as its general 5 shape is concerned, resembles in a way, the shell-member of a paper slide-box, it is clearly distinguished from such a box-shell by reason of the structural characteristics herein set forth in detail and as pointed out 10 in the appended claims.

What I claim is:—

1. As a new article of manufacture, a pocket cigarette case comprising a substantially rectangular shell open at two opposite 15 ends and adapted to slidably receive and frictionally embrace and retain a cigarette-slide box inserted therein, the outer walls of said shell having a leather covering applied thereto, the marginal edges of the said covering being turned or folded over the open 20 ends of the shell and affixed to the inner walls thereof, said inturned marginal edges

being exposed within the shell for direct contact with the walls of the cigarette box to frictionally retain the latter in the shell. 25

2. As a new article of manufacture, a pocket cigarette case comprising a box-form shell open at two opposite ends and adapted to slidably receive and retain a cigarette slide-box inserted therein, said shell being 30 slightly narrower at one end than at the other and having a covering of flexible wear-resisting material applied to the outer walls thereof reinforcing the corners of said shell, substantially as and for the purpose 35 described.

In testimony whereof I have hereunto set my hand in presence of two subscribing witnesses.

GEORGE W. HILL.
